LOCK DEVICE FOR WELL TOOLS

Reuben C. Baker, Coalinga, Calif., assignor to
 Baker Oil Tools, Inc., Vernon, Calif., a corpora-
 tion of California

Application August 15, 1942, Serial No. 454,951

8 Claims. (Cl. 166—12)

This invention relates to well tools, and more particularly to the locking portions of tools designed for subsurface operations in well bores.

Locking devices are used in connection with many well tools designed for operations in well bores. One of the most common of such devices is a J-pin and slot arrangement employed in connection with packers, liner hangers, tubing anchors, well washers, etc. Such J, L and similar types of locks can function to maintain certain well tool parts in a definite position, or they can be manipulated to release such parts and permit their performance of the particular action or operation in the well bore, such as to set a packer or liner therein, control a valve, etc. Difficulties are sometimes encountered in unlocking this type of device, and in relocking it after it has been released from locked position. One reason for this latter difficulty resides in the necessity for moving the entire running-in string to which the tool is attached longitudinally to a particular and relatively fixed position, wherein the J-pin is located adjacent the horizontal portion of the J-slot, before the string can be rotated in the proper direction to effect movement of the J-pin into the horizontal locking slot portion. It is apparent that the inability to manipulate the running-in string to so locate the pin will preclude locking or relocking of the tool parts.

Accordingly, it is an object of the present invention to overcome the aforementioned difficulties by providing a well tool device which can function to lock or relock parts of the tool in the particular position required without the necessity for moving the running-in string to any particular, predetermined position.

A further object of the invention is to provide a subsurface well tool embodying a releasable coupling or clutch capable of locking elements of a device in a well bore in a desired position. As a more limited feature of this objective, such releasable coupling or clutch may be adapted to lock casing engaging means, such as slips or packings, in retracted position.

Still a further object of the invention is to provide an automatically engageable clutch in a well device whose disengagement is controlled by a running-in string attached to the device.

A further object of the invention is to provide a one-way or overrunning clutch type of lock device in a well tool adapted to permit release of the tool at will upon longitudinal movement of the running-in string in one direction, but which locks certain of the tool parts with respect to one another upon manipulation of the run-

ning-in string in the other longitudinal direction.

Yet another object of the invention is to provide a clutch type of lock device for a well packer which automatically releases to permit movement of packer anchoring elements with respect to a packer expander upon lowering of the running-in string to which the packer is attached, and which automatically locks such anchoring elements to prevent such movement upon elevation of the running-in string. In a preferred form of the invention, the locking action is automatically increased during elevation of the running-in string.

Another object of the invention is to provide a clutch device in a subsurface well tool for controlling movement of parts of the tool with respect to each other, in which engagement and disengagement of the clutch is controlled from the surface of the well bore through manipulation of the running-in string to which the tool is attached.

The invention has other objects that will become apparent from a consideration of the embodiment shown in the drawings accompanying and forming part of the present specification. This form will now be described in detail, but it is to be understood that such detailed description is not to be taken in a limited sense, since the scope of the invention is best defined by the 30 claims appended hereto.

Referring to the drawings:

Figure 1 is a longitudinal view, partly in section and partly in elevation, of a well packer embodying the present invention, with its parts 35 in retracted position for movement through a well bore or casing;

Figure 2 is a cross section taken along the line 2—2 in Figure 1;

Figure 3 is a cross section on an enlarged scale 40 taken along the line 3—3 in Figure 1;

Figure 4 is a longitudinal section of part of the device taken along the line 4—4 in Figure 3;

Figure 5 is a cross section taken along the line 5—5 in Figure 1;

Figure 6 is a view similar to Figure 1 disclosing the well packer with its parts in packed off condition within a well casing;

Figure 7 is a cross section on an enlarged scale taken along the line 7—7 in Figure 6; and

Figure 8 is a view similar to Figure 4 disclosing the position occupied by parts of the clutch portion of the well tool upon its elevation within the well bore.

The invention is exemplified in the drawings as forming part of a well packer of the retray-

able type. It is to be understood, however, that the invention is also applicable to other well tools, as the following detailed description of the apparatus shown in the drawings will bring out.

The packer illustrated in the drawings is specifically described and particularly claimed in my application for "Releasable well packers," Serial No. 419,061, filed November 14, 1941. This packer A is adapted to be run in a well bore or casing B on the end of a tubular running-in string C 10 threadedly or otherwise attached to the upper end of the tubular mandrel 10 of the packer. The lower end of this mandrel is threaded into the upper end of a tubular packer body 11, to the lower end of which is secured a packing actuator 12 in the form of a guide.

A tapered expander 13 mounted on the body is preferably prevented from turning with respect thereto by a key 14 secured to the exterior of the body 11 and received within a keyway 15 in the expander, so as to permit relative longitudinal movement between the body and expander, while preventing rotation therebetween. When the tubular string C, mandrel 10 and body 11 are elevated, the packing actuator 12 is moved towards the expander 13 to compress an intervening packing sleeve 16 surrounding the body and force it outwardly to effect an annular seal between the body 11 and casing B. Such actuation of the packing sleeve 16 only occurs when the tapered expander 13 is prevented from moving upwardly, which results from anchoring engagement by a plurality of slips 17 cooperating with the tapered expander with the wall of the casing. The slips 17 have tapered surfaces 18 cooperable with companion tapered surfaces 19 on the expander, the inclination of such surfaces being such as to move the slips 17 outwardly toward the casing upon elevation of the expander 13. Conversely, lowering of the expander with respect to the slips permits the latter to release from anchoring engagement with the wall of the casing and move inwardly to retracted position.

It is therefore apparent that elevation of the tubular string C, mandrel 10 and packer body 11 can effect anchoring of the tool in packed off condition through engagement of the slips 17 with the casing under the influence of the tapered expander 13, and they can also effect compression of the packing sleeve 16 between the expander 13 and guide 12 to produce its radial outward expansion into sealing engagement with the wall of the casing.

The slips 17 are held together for joint movement along the tapered expander 13 to and from engagement with the casing by providing recesses 20 in their side faces which receive outwardly extending fingers 21 for guiding the slips to and from the casing, and for preventing their longitudinal movement except in unison by engaging the ends of the recesses 20. These fingers 21 are integral with a sleeve 22 slidable on the mandrel 10, which has a stop ring 23 secured thereto by screws 24 or the like for the purpose of limiting the extent of outward movement of the slips.

This sleeve 22, and the slips 17 assembled thereon, are coupled to a drag and lock device 25, comprising a lower collar 26 slidable on the mandrel 10, which receives the lower ends of a plurality of circumferentially spaced outwardly bowed friction springs 27 held thereagainst in assembled relation by a ring 28 fastened to the collar by a plurality of screws 29. These springs are disposed around the mandrel with their upper

ends secured to an upper drag collar or releasable coupling or clutch device 30 by an upper ring 31 suitably fastened thereto, as by screws 32.

The drag and lock device 25 is coupled to the slip assembly by means of a sectional tie or coupling ring 33 secured to the lower collar 26 by screws 34, and having a lower inturned flange 35 receiving and fitting under an external flange 36 at the upper end of the slip sleeve 22. Rotation of the tubular string C, mandrel 10 and drag device 25 is permitted without corresponding rotation of the slip assembly sleeve 22 and slips 17, due to the swivel type of action provided by the lower end of the coupling ring 33 and sleeve flange 36.

It is to be noted that the drag device 25 engages the casing wall and thereby tends to resist longitudinal movement of the slips 17 coupled thereto through the well casing. Upon reaching the desired setting point in the casing, if the tubular mandrel 10 is permitted to move upwardly with respect to the drag device, such elevation would also elevate the body 11 of the packer, and through the guide 12 and packing sleeve 16 elevate the expander 13 within the slips 17, since the latter are prevented from moving upwardly by the drag device, to force the slips radially outwardly into anchoring engagement with the casing wall. A continuation of such upward movement causes compression of the packing sleeve 16 into sealing engagement with the casing B and body 11, in the manner hereinbefore described. Conversely, lowering of the tubular mandrel 10 with respect to the drag device 25 permits retraction of the packing sleeve 16 from the casing wall and produces corresponding downward movement of the tapered expander 13, through engagement of the body shoulder 37 with the expander flange 38, so that the slips 17 are movable inwardly to retracted position, since they are prevented from moving longitudinally by the drag device.

It is important to note that upward movement of the tubular mandrel 10 and body 11 can effect anchoring of the packer in packed off condition within the well casing, and that lowering of these members can effect release of the packer. It is, therefore, essential that some means be provided for preventing relative movement between the slips 17 and the tapered expander 13 in order to allow the tubular mandrel 10 to be elevated without anchoring the tool in the well casing when the entire tool is to be raised within the well casing.

The usual device for locking slips with respect to an expander, or for that matter, for preventing relative movement until desired between co-operable parts of subsurface well tools generally, is a J type of lock. Such lock can include a pin operable within a longitudinal slot and an intersecting horizontal slot. When the pin is positioned in the horizontal slot, the tool members are locked; and when the pin is positioned for movement in the longitudinal slot, the tool members are unlocked and the tool may be manipulated in the desired fashion, depending upon its design and the purpose for which it is to be used. Such devices can only be locked when the J-pin occupies a single, predetermined position with respect to the slot, namely, in the horizontal portion thereof. If the pin and slot cannot be moved with respect to each other to proper position, locking of the tool parts cannot occur.

The foregoing disadvantages and difficulties are exceedingly pronounced when a J type of lock is used in connection with a retrievable well

packer of the type illustrated in the drawings. The inability to relock the slips 17 with respect to the expander 13 might preclude retrieval of the tool from the well bore, since the expander could move upwardly within the slips and anchor them and the packer in the casing, in the event that the J-pin could not be reinserted into the horizontal portion of the slot. It might be possible to lower the tubular string and mandrel sufficiently to release the slips from the casing, but unless the mandrel is lowered sufficiently so as to permit relocation of the pin in the horizontal slot portion, the taking of an upward strain on the tubular string and mandrel would immediately set the slips again, since the J-pin would still be free to move within the longitudinal slot portion.

The present invention overcomes such disadvantages and difficulties through its ability to effect relocking of the slips 17 despite the fact that the tubular mandrel 10 has not been moved completely to a predetermined locking position. As disclosed in the drawings, the locking device is incorporated in the upper collar 30 of the drag device. Essentially, this device is a releasable coupling or clutch, preferably of the overrunning or one-way type. The upper portion of the mandrel 10 movable through the upper collar is formed with a series of circumferential teeth 39 adapted for engagement with corresponding teeth 40 formed in a coupling or clutch element, consisting of a split ring 41 surrounding the mandrel. This ring is provided with external, spaced grooves or notches 42 to increase its flexibility. The ends 43, 44 of this ring are spaced apart from one another to a substantial extent, leaving a circumferential space 45 in which the inner end 46 of a stop member 47 extends. This member 47 may take the form of a pin threaded into the collar 30 with its inner end 46 tapered for cooperation with a corresponding taper on the trailing end 44 of the ring. The external surface 48 of the ring is tapered in an upward and inward direction for cooperation with a corresponding taper, wedge or cam surface 49 formed in the collar 30. The ring 41 is held in the collar and is prevented from dropping therefrom by a closure 50 fastened to the lower end of the collar by screws 51, and preferably having a downwardly extending sleeve 52 for guiding and holding the upper collar 30 of the drag device 25 coaxially of the mandrel 10.

The mandrel 10 is provided with a longitudinally extending clutch actuator or releasing key 53, which is suitably secured to the mandrel and extends along its teeth 39. This key extends between the ends 43, 44 of the clutch ring, and is designed to engage the leading end 43 of such ring to control its movement to and from clutching engagement with the teeth 39 on the mandrel. Such control results from angular movement of the mandrel 10 within the upper collar 30, and to permit this angular movement to occur, the collar and closure are provided with internal longitudinal grooves 56, 57 through which the key extends.

The clutch ring 41 is of the contractile type, and inherently tends to move inwardly into coupling engagement with the teeth 39 on the mandrel, to couple the collar 30 of the drag device 25 to the mandrel 10, and thereby indirectly couple the slips 17 thereto and prevent relative movement therebetween. Whenever release of the coupling ring 41 from the mandrel 10 is desired, the mandrel is rotated a partial revolution

so that the releasing key or clutch actuator 53 engages the leading end 43 of the ring to expand it from engagement with the mandrel teeth 39.

It is to be noted that the drag device 25 engages the casing to prevent movement of the collar 30 and the stop pin 47. As a result, turning of the tubular string C and mandrel 10 a partial revolution (in a clockwise direction, as seen from the surface of the bore hole) causes the releasing key 53 to engage the leading end 43 of the clutch ring, forcing its trailing end 44 against the tapered end 46 of the comparatively stationary stop pin. The inclination on the trailing end 44 and the companion inclination on the stop pin 46 is such that engagement therebetween moves the trailing end outwardly sufficiently so that its teeth 40 no longer engage the teeth on the mandrel. A continuation of the ring movement through engagement of its leading end 43 by the releasing key 53 expands the ring 41 outwardly until its teeth are entirely free of the mandrel teeth (see Figure 7), which effects uncoupling of the upper drag collar 30 from the mandrel and permits upward movement 20 of the mandrel 10 with respect to the drag device. This action is necessary in anchoring the packer in packed off condition in the well casing. Continuation of the clockwise strain on the tubing string C maintains the ring 41 in unlocked or unclutched position during elevation of the tubular mandrel 10, due to the slidable engagement of the extended releasing key 53 with the leading end 43 of the ring during its elevation with the mandrel. Release of such clockwise strain on the tubular string and mandrel at any time immediately permits automatic contraction of the ring 41 into engagement with the teeth 39 of the mandrel, and immediately locks the drag device 25 thereto, so as to preclude further relative movement between the slips 17 and mandrel 10, and consequently, between the expander 13 and slips 17.

The teeth 39 on the mandrel are preferably of the ratchet type for use of the invention in connection with the packer disclosed in the drawings. Such teeth face in an upward direction and the corresponding teeth 40 on the coupling ring 41 face in a downward direction, to permit downward ratcheting of the mandrel 10 with respect to the ring 41, but, nevertheless, automatically coupling the mandrel to such ring and the collar 30 upon upward movement of the mandrel, except when the ring is expanded under the turning action of the mandrel 10 and key 53, as described above. Moreover, it is to be noted that the engagement between the upwardly and inwardly inclined tapered surfaces 48, 49 on the ring 41 and collar or housing 30 increases the wedging action of the ring against the mandrel upon its upward movement within the casing.

In running the tool downwardly within the well bore, it is immaterial whether the releasing key 53 and stop pin 47 hold the clutch ring 41 in coupled or released position, since the ratchet teeth 39 on the mandrel permit downward movement of the mandrel through the ring and upper collar 30. Due to the resistance of the drag device 25 against the casing, which tends to hold the slips 17 in an upward position, such downward movement holds the packing sleeve 16 and slips 17 in retracted position. If desired, a stop pin 54 may be provided on the mandrel 10 engageable with the lower collar 28 to positively limit the extent of downward movement of the

packer parts, and especially of the tubular mandrel 10 within the upper clutch collar 30. When moving downwardly within the well casing B, the clutch ring 41 is positioned against the closure 50, or in the lowermost portion of the collar 30, where there is ample room for the ring to expand outwardly, because of the material clearance 55 or maximum width between the exterior of the ring 41 and the tapered surface 49 in the collar 30 (see Figures 1 and 4).

When the point is reached at which it is desired to set the packer, the tubular string C and mandrel 10 are turned a slight angular distance in a clockwise direction, to cause the slideable key 53 to engage the leading end 43 of the ring 41 and force its trailing end 44 against the stop pin 47, so that a slight additional turn of the mandrel and key effects disengagement of the ring 41 from the mandrel teeth 39, permitting the mandrel 10 to be elevated upwardly and effect upward movement of the expander 13 within the slips 11, which will force them outwardly into anchoring engagement with the casing B, and which will allow subsequent compression of the packing sleeve 16 between the casing B and the packer body 11. The mandrel 10 remains uncoupled from the drag device 25 and slips 11 so long as such rotational strain is placed on the contractile ring 41 to hold it in expanded position clear of the mandrel teeth 39. Immediately upon release of the ring 41, it automatically engages the ratchet teeth 39 on the mandrel 10.

When it is desired to release the well packer from the casing, the tubular running in string C and mandrel 10 are merely lowered, and the packing sleeve 16 and slips 11 moved to retracted position, since the drag device 25 tends to hold the slips 11 stationary and the mandrel 10 is free to ratchet through the clutch collar 30 and its ratchet ring 41, in the same manner as an overrunning or one-way clutch type of coupling device operates. As soon as the tubular string C and mandrel 10 are elevated, however, the collar 30 and clutch ring 41 are automatically coupled to the mandrel to prevent the expander 13 from moving upwardly within the slips 11, which action would anchor them to the casing. The tool can now be removed from the well bore, even though the mandrel 10 has not been lowered through the drag device to the fullest extent possible, as is necessary in the J-types of lock devices. In any position in which upward movement of the mandrel 10 takes place, the drag device 25 and slips 11 are immediately coupled thereto to preclude their relative movement. The only condition under which the mandrel 10 can move upwardly with respect to the drag device 25 is one in which the tubular string C and mandrel 10 are rotated in the proper direction to release the coupling ring 41 from the ratchet teeth 39.

Once elevation of the well packer with its parts in retracted position has begun, to remove the tool from the well bore, or to locate it in another position, the drag device 25 remains locked to the mandrel 10, and this locking action is increased by the wedging of the ring 41 against the tapered surface 49 of the collar 30, which tends to add its locking force to the inherent characteristic of the ring 41 to contract and remain in locked position on the mandrel (see Figure 8).

It is therefore apparent that a lock device has been provided, which can function to couple the elements of a well tool together in various positions of the device, rather than in only a single,

predetermined position thereof, as in the prior art devices. The locking device automatically uncouples upon longitudinal movement of one of its members in one direction, and can be selectively manipulated from the surface of the well bore to control its coupling action upon longitudinal movement of said member in either direction.

I claim:

1. A well tool adapted for operation in a well bore, including a mandrel connectable to a running-in string for moving said tool within said well bore, a clutch collar surrounding said mandrel, a split clutch ring engageable with said mandrel and collar for automatically locking them together upon movement of said mandrel in one longitudinal direction within said well bore and for automatically releasing them from one another to permit longitudinal movement of said mandrel within said collar upon movement of said mandrel in the other longitudinal direction within said well bore, means on said collar engageable with said clutch ring to prevent its rotation, and means on said mandrel engageable with said ring to expand it from engagement with said mandrel upon rotation of the latter to permit longitudinal movement of said mandrel in both directions within said collar.

2. A well tool adapted for operation in a well bore, including a mandrel connectable to a running-in string for moving said tool within said bore, a clutch collar surrounding said mandrel, a split clutch ring engageable with said mandrel and collar for locking them together, means on said collar engageable with said clutch ring to prevent its rotation, and means on said mandrel engageable with said ring to expand it from engagement with said mandrel upon rotation of the latter to permit longitudinal movement of said mandrel in both directions within said collar.

3. A well tool, including a mandrel connectable to a running-in string for moving said tool within a well casing, slips for anchoring said tool to said well casing, an expander movable within said slips for shifting them to casing anchoring position upon elevation of said mandrel within said well casing, a drag device coupled to said slips and engageable with said casing to resist movement of said slips therewithin, clutch means comprising a split, contractile ring for locking said drag device to said mandrel to prevent expansion of said slips by said expander to casing anchoring position upon elevation of said mandrel, means on said drag device engageable with said ring to prevent its rotation, and means on said mandrel engageable with said ring to expand it from engagement with said mandrel upon rotation of the latter to permit said mandrel to move within said drag device and wedge said expander within said slips.

4. A well tool, including a mandrel connectable to a running-in string for moving said tool within a well casing, slips for anchoring said tool to said well casing, an expander adapted to be wedged upwardly in said slips to shift them to casing anchoring position upon elevation of said mandrel within said well casing, a drag device coupled to said slips and engageable with said casing to resist movement of said slips therewithin, a split clutch ring engageable with said mandrel and drag device for locking them together to prevent wedging of said expander in said slips upon elevation of said mandrel, means on said drag device engageable with said clutch ring to prevent its rotation, and means on said mandrel engageable with said ring to render it

ineffective upon rotation of the mandrel to permit elevation of said mandrel within said drag device and effect upward wedging of said expander within said slips.

5. A well tool, including a mandrel connectable to a running-in string for moving said tool within a well casing, normally retracted means carried by said mandrel for engagement with said casing, means operable by said mandrel for expanding said normally retracted means into engagement with said casing, clutch means releasably locking said mandrel and casing engaging means together to hold the latter in retracted position with respect to said casing, said clutch means comprising a clutch collar surrounding said mandrel and a laterally movable clutch element coupling said mandrel and collar together, means on said clutch means engageable with said casing to resist movement of said clutch means therewithin, and means responsive to movement of said mandrel for shifting said clutch element laterally to uncoupling position to permit said expanding means to be moved by said mandrel with respect to said normally retracted means to shift the latter into engagement with said casing.

6. A well tool, including a mandrel connectable to a running-in string for moving said tool within a well casing, normally retracted means carried by said mandrel for engagement with said casing, means operable by said mandrel for expanding said normally retracted means into engagement with said casing, clutch means releasably locking said mandrel and casing engaging means together to hold the latter in retracted position with respect to said casing, said clutch means comprising a clutch collar surrounding said mandrel and a clutch element adapted to be wedged between said mandrel and collar for locking them together, means on said clutch means engageable with said casing to resist movement of said clutch means therewithin, and means responsive to movement of said mandrel for moving and holding said clutch element from its wedged position between said mandrel and collar to permit said expanding means to be moved by said mandrel with respect to said nor-

mally retracted means to shift the latter into engagement with said casing.

7. A well tool, including a mandrel connectable to a running-in string for moving said tool within a well casing, slips for anchoring said tool to said well casing, expander means for moving said slips to casing anchoring position upon upward longitudinal movement of said mandrel within said well casing, means on said mandrel connecting said slips for joint movement within said casing, a clutch element adapted to be wedged between said mandrel and connecting means for releasably locking said mandrel and slips together to prevent movement of the latter to casing anchoring position upon upward movement of said mandrel, means on said connecting means engageable with said casing to resist movement of said connecting means therewithin, and means responsive to rotation of said mandrel for moving and holding said clutch element from its wedged position between said mandrel and connecting means to permit upward longitudinal movement of said mandrel with respect to said slips and shifting of the latter by said expander to casing anchoring position.

25 8. A well tool, including a mandrel connectable to a running-in string for moving said tool within a well casing, slips for anchoring said tool to said well casing, an expander movable within said slips for shifting them to casing anchoring position upon elevation of said mandrel within said well casing, a drag device coupled to said slips and engageable with said casing to resist movement of said slips therewithin, clutch means comprising a clutch element adapted to be wedged between said mandrel and drag device for locking them together to prevent expansion of said slips by said expander to casing anchoring position upon elevation of said mandrel, and means responsive to rotation of said mandrel for moving and holding said clutch element from its wedged position between said mandrel and drag device to permit said mandrel to move within said drag device and correspondingly move said expander within said slips.

REUBEN C. BAKER.
